UNITED STATES PATENT OFFICE.

JAMES N. SAWKINS, OF PHILADELPHIA, PENNSYLVANIA.

IMPROVEMENT IN SPARK AND DUST ARRESTERS FOR LOCOMOTIVES.

Specification forming part of Letters Patent No. 176,071, dated April 11, 1876; application filed October 23, 1875.

To all whom it may concern:

Be it known that I, JAMES N. SAWKINS, a subject of the Queen of Great Britain, temporarily residing at Philadelphia, in the county of Philadelphia and State of Pennsylvania, have invented certain new and useful Improvements in Locomotive Smoke-Stacks and Dust-Arresters, of which the following is a specification:

My invention consists, first, in combining, with the smoke-stack of the locomotive, an adjustable annular deflecting funnel or conductor interposed between the outer shell and the inner flue, within which the blast and the products of combustion from the furnace are received. The said deflecting funnel serves to carry downward the products of combustion into a water-reservoir, by which all sparks and dust are arrested. The invention further consists in combining with the water-reservoir and deflecting funnel a discharge-pipe and dust-receiver adapted to conduct the water, dust, and cinders from the chamber within the stack and discharge them upon the ground or upon the rails near the driving-wheels, or to retain the ashes and other matter eliminated from the smoke for use in lieu of sand for increasing the traction of the wheels when occasion may require. The invention further consists in the combination of a cowl or hood of peculiar construction with a smoke-stack, as hereinafter described.

In the accompanying drawings, Figure 1 is a side elevation of a portion of a locomotive, illustrating the invention. Fig. 2 is a top view of the same. Fig. 3 is a vertical longitudinal section of the stack on a larger scale, on the line 3 3, Fig. 4. Fig. 4 is a horizontal section in two planes, indicated by the lines 4 4, Fig. 3. Fig. 5 is a side elevation of the dust-receiver and its accessories. Fig. 6 is a rear view of the same. Fig. 7 is a top view thereof. Fig. 8 is a vertical longitudinal section on the line 8 8, Fig. 7. Figs. 9 and 10 are, respectively, a side elevation and a plan partly in section, illustrating a modification.

A may represent portions of the frame, B the boiler, C the pilot, and D D driving-wheels of a locomotive of ordinary construction. E represents the smoke-stack, and F a frusto-conical cowl placed in horizontal position

above the same, with the smaller end forward, as shown. The effect of the cowl thus formed and placed is to induce a powerful upward draft through the stack by the resistance of the atmosphere when the engine is in motion. G represents an internal flue within which the blast is delivered and the products of combustion are carried from the furnace. The upper end of the flue G is surmounted by a hood, H, leaving sufficient space above for the passage of the blast and gaseous products of combustion, together with any cinders or dust that may be carried by the blast up through the flue G. The hood H extends downward between the flue-pipe G and shell E, and communicates at its lower end with a discharge-funnel, I, forming a continuation of said hood and fitting within or around it, as preferred, so that it may be slipped up and down to vary the level at which the smoke and other matters are discharged from the said hood and funnel H I. The lower part of the shell E constitutes a water-chamber, J, the discharge-funnel I being set up or down to regulate its depth of immersion and the freedom of draft and insure a thorough elimination of cinders, &c., from the smoke while the engine is in motion. The lower end of the funnel I is preferably made flaring outward, as shown, and the lower parts of the flue G and shell E forming the inner and outer walls of the annular water-chamber of a corresponding shape. K represents a rack attached to the discharge-funnel I. L is a cogged segment gearing with said rack and operated by an arm, M, and rod N, for the purpose of moving the funnel I up or down. O is a pipe for introducing water into the chamber J. P P are discharge-pipes, through which the water may overflow from the chamber J, together with dust, cinders, and other solid matters which are separated from the smoke and are constantly stirred up in the water by the action of the blast. The pipes P P communicate at their lower ends with eccentric nozzles Q, which may be turned through the medium of pinions R, by means of segment-racks S and rods T, so as to place the eccentric nozzles Q in communication with the dust-receivers U, as illustrated in full lines in Fig. 8, or with discharge-pipes V, as illustrated in dotted lines. q is a flange attached to the lower

end of each eccentric nozzle for the purpose of closing the opening into the reservoir U when the nozzle is adjusted to the discharge-pipe V. The reservoirs U are furnished with perforated sliding bottoms W, to permit a free discharge of water, but to retain dust and cinders within the reservoirs, if desired. The sliding bottoms are operated by levers X and rods Y, to enable the engineer to discharge the cinders on the rails in front of or between the driving-wheels, when occasion may require, in order to increase the traction of said wheels.

Operation : The conical cowl F creates a forcible draft upward through the stack, so as to more than compensate for any obstruction caused by the water in the chamber J. When the engine is standing still the funnel I may be thrown up to or above the surface of the water, so as to allow the smoke to pass off freely. When the apparatus is in full operation the solid matter carried out of the furnace with the smoke is thrown under the body of water contained in the chamber J and there retained, the blast agitating and maintaining a constant ebullition of the water so as to throw it up and cause it to pass to the discharge-pipes P, carrying with it the matters eliminated from the smoke. A sufficient supply of water is introduced through the pipe O, either constantly or at intervals. The use of the reservoirs U may be dispensed with, or the perforated bottoms W may be kept constantly withdrawn when the condition of the road does not demand an occasional and plentiful use of the dust and cinders to increase traction. If, however, the apparatus be used as illustrated in the drawings, the reservoirs U retain the dust and cinders. The engineer is thus provided with a most effective material for scat-

tering on the rails to increase the traction of the wheels when an emergency may require it, thus dispensing entirely with the necessity of sand-boxes.

Z are the outlet-pipes from the reservoirs U.

In the illustration shown in Figs. 9 and 10 the reservoirs U are dispensed with, the discharge-pipes being extended down nearly to the rails and terminating in eccentric nozzles Q, adjustable by means of rods T; or equivalent means, so as to direct the discharge on or off the rails, as desired.

Having thus described my invention, what I claim as new, and desire to secure by Letters Patent, is—

1. The combination, with the shell E, of the central flue G, the deflecting hood H, and the adjustable annular funnel I, substantially as and for the purposes set forth.

2. The combination of the water-chamber J, the supply-pipe O, and the discharge-pipes P, the shell E, flue G, and deflecting hood or funnel H I, as and for the purposes set forth.

3. The reservoirs U, provided with perforated discharge-valves W, in combination with the dust-arresting apparatus, constructed to operate substantially as herein set forth.

4. The eccentric nozzle Q, in combination with the discharge-pipe P, as and for the purposes set forth.

5. The frusto-conical cowl F, in combination with the shell E, flue G, and deflecting hood and funnel H I, substantially as and for the purposes set forth.

J. N. SAWKINS.
